UNITED STATES PATENT OFFICE.

BURTON E. HULL, OF HOUSTON, TEXAS, ASSIGNOR TO THE TEXAS COMPANY, A CORPORATION OF TEXAS.

EXPLOSION-HATCH FOR OIL-TANKS.

1,396,719.

Specification of Letters Patent.

Patented Nov. 8, 1921.

Application filed January 30, 1920. Serial No. 355,278.

To all whom it may concern:

Be it known that I, BURTON E. HULL, a citizen of the United States of America, and a resident of Houston, county of Harris, 5 and State of Texas, have invented certain new and useful Improvements in Explosion-Hatches for Oil-Tanks, of which the following is a specification, reference being had to the accompanying drawings, forming 10 a part thereof.

This invention relates to explosion hatches for oil tanks and other containers, and has special reference to hatches for the steel roofs of large oil storage tanks.

One object of this invention is to provide 15 a hatch of the aforesaid character which will readily permit, with a minimum of pressure within the tank, of the escape of the combustion gases through the hatchway, 20 without damage to the hatch in case an explosion should occur within the tank.

It has been the aim of this invention to avoid the leakage which has interfered with the operation of hatches as hitherto constructed and to avoid other troubles and disadvantages which are well known to those skilled in this art.

Other objects and advantages of this invention will be set forth hereinafter, and in 30 order that it may be understood in detail, a preferred embodiment of the same is shown in the accompanying drawings, in which:

Figure 1 is a sectional elevation showing 35 an explosion hatch arranged and constructed in accordance with this invention.

Fig. 2 is a sectional plan view, taken on the line 2-2 of Fig. 1.

In the drawings, 10 designates the steel 40 roof of a storage tank adapted to contain petroleum oil or the like.

An opening 11 in the roof is provided with a hollow cylindrical projection 12 to constitute a hatchway 13 which is normally 45 closed by a hatch 14 having a substantially horizontal upper surface of considerable area.

The cylindrical projection 12 has an annular flange 15 which cooperates with the 50 outer edge of the projection 12 in the formation of an annular groove or trough 16 which is adapted to receive a downwardly extending annular rib 17 with which the hatch is equipped. The hatch furthermore has

an overhanging flange 18 to prevent the 55 water from getting into the trough or groove 16. At the center, the hatch 14 is provided with a lug 19 and a central opening 20 in which a tubular guide rod 21 is affixed.

A strong and rigid stationary frame 22 is securely mounted on the tubular projection 12 of the tank and comprises a stop plate 23 having a central hole and bearing 24, and a plurality of vertical supporting bars 25 having radial extensions 26 to 65 which the stop plate 23 is secured. The stop plate 23 has a substantially horizontal lower surface of considerable area to be engaged by the corresponding upper surface of said hatch 14. The vertical rods 25 are mounted 70 at their lower ends on stationary brackets 27 which are affixed to the tubular projection 12. Furthermore, a central guide bearing 28 is supported by radial arms 29 within the hatchway opening. 75

The tubular guide rod 21 which is affixed to the hatch is sufficiently long to extend upwardly through the guide bearing 24 when the hatch is closed and downwardly through the guide bearing 28 far enough 80 to prevent its riding out of the bearing when the hatch is forcibly thrown up against the stop plate 23.

The structure may of course be made of any suitable material, but I prefer to make 85 the hatch of aluminum and the tube 21 of brass or the like so that the hatch with its connected parts is very light and strong. It is thus adapted to respond easily and quickly to a slight increase of pressure with- 90 in the tank.

It is particularly necessary to seal the joint between the hatch and the tank in order to prevent leakage and, according to this invention, this is accomplished by filling 95 in the trough or groove 16 with a mixture of paraffin and sand. Another material which has been employed with good success and may be considered preferable is cup grease having a melting point of about 100 400° F.

The arrangement is such that when the hatch is in position the rib or flange 17 forms a groove in the grease or sealing mixture in the trough 16 and a gas-tight seal 105 is effected. The tubular rod 21 is provided with a cap 30 at the top to prevent leakage from the tank through the tube.

In operation if an explosion occurs within the tank by reason of a lightning discharge, or for other cause, the aluminum hatch is thrown upward violently against the strong and rigid plate 23 and after bouncing up and down two or three times, relieving the pressure, it shuts the hatchway and seals it so that fire in the tank is extinguished, the tank being air-tight and filled with inert gas, so that further combustion is impossible. The construction and arrangement of the supporting frame 22 and the stop plate 23 insures the positive arrestment of the hatch even though the action may be extremely violent. Hence, the hatch is in position and in readiness to close the hatchway and prevent further combustion.

It is important to avoid the use of any material which will harden around the flange 17 of the hatch and thus elevate the pressure necessary to lift the hatch.

Various other advantages of the foregoing invention will be apparent to those skilled in this art, but attention may be directed to the fact that the hatch is free from hinges and other localized connections to the tank which tend to interfere with its opening readily. The hatch is preferably made of light material which is not oxidized by moisture and permits the hatch to be readily lifted. Furthermore, the seal is one which prevents leakage of gas and yet does not interfere with the sensitiveness of the hatch in action.

As an illustration of difficulties hitherto encountered, hatches of the hinge type have in some cases been blown entirely off their hinges and in other cases they have been thrown open but failed to close, tight enough to prevent the continuation of fire within.

A structure of preferred form has been illustrated and described for the purpose of showing a way in which this invention may be used, but the inventive thought upon which this application is based, is broader than this illustrative embodiment thereof, and no limitations are imposed other than those in appended claims.

Claims:

1. The combination with a closed tank having a hatchway, of a hatch for closing the hatchway, a rod attached to the hatch, a guide frame secured to the tank and having guide bearings for the rod to allow the hatch to open and close as the rod slides in the guide bearings, and means disposed above said hatch and secured to said tank for limiting the outward movement of said hatch by engagement therewith.

2. The combination with a closed tank having a hatchway, a hatch for closing the hatchway, a vertical rod secured to the hatch and extending outwardly therefrom, a frame secured to the tank and extending above said hatch and having a stop adapted

to be engaged by said hatch to limit the outward movement thereof and a guide bearing for the vertical hatch rod.

3. The combination with a closed tank having a hatchway, of a hatch adapted to close the hatchway, a central rod secured to the hatch and extending outwardly and inwardly therefrom, a guide bearing secured in the opening of the hatchway for guiding the inner end of the rod, and a guide bearing supported from the tank and spaced above the hatchway for guiding the outer end of the hatch rod.

4. The combination with a closed tank having a hatchway, of a hatch adapted to close the hatchway, a central rod secured to the hatch and extending outwardly and inwardly therefrom, a guide bearing secured in the opening of the hatchway for guiding the inner end of the rod, and a guide bearing supported from the tank and spaced above the hatchway for guiding the outer end of the hatch rod and for limiting the outward movement of the hatch by engagement therewith.

5. The combination with a roof tank having a hollow cylindrical projection extending vertically and forming a hatchway, a hatch adapted to rest upon the cylindrical projection and close the hatchway, means for guiding the hatch in a straight line vertical motion, and means rigidly secured to said cylindrical projection and disposed above said hatch to be engaged thereby for limiting movement thereof in an outward direction.

6. The combination with a roof tank having a hollow cylindrical projection extending vertically upward and forming a hatchway, a hatch adapted to rest upon the cylindrical projection and close the hatchway, a frame having a stop plate spaced above the hatch opening and adapted to be engaged by said hatch for limiting the outward movement thereof, a guide bearing within the hatch opening, and a hatch rod extending inwardly through the guide bearing and adapted to guide the hatch in a vertical direction.

7. The combination with a roof tank having a hollow cylindrical projection extending vertically and forming a hatchway, a hatch adapted to rest upon the cylindrical projection and close the hatchway, a frame having a stop plate spaced above the hatch opening and adapted to be engaged by said hatch for limiting the outward movement thereof, a guide bearing within the hatch opening, a second guide bearing at the stop plate, a rod secured to the hatch and extending vertically outward through the guide bearing in the stop plate and inwardly through the guide bearing in the hatchway.

8. The combination with a closed tank having a hatchway, a hatch for closing the

- hatchway, a vertical rod secured to the hatch and extending outwardly therefrom, a frame secured to the tank and extending above said hatch and having a stop adapted to be engaged by said hatch to limit the outward movement thereof and a guide bearing for the vertical hatch rod, said hatchway being arranged to form an annular groove containing a sealing material and said hatch having a rib arranged to extend into said groove.
9. The combination with a closed tank having a hatchway, of a hatch adapted to close the hatchway, a central rod secured to the hatch and extending outwardly and inwardly therefrom, a guide bearing secured in the opening of the hatchway for guiding the inner end of the rod, a guide bearing supported from the tank and spaced above the hatchway for guiding the outer end of the hatch rod and for limiting the outward movement of the hatch by engagement therewith, said hatchway being arranged to form an annular groove containing a sealing material and said hatch having a rib arranged to extend into said groove.
10. The combination with a roof tank having a hollow cylindrical projection extending vertically and forming a hatchway, a hatch adapted to rest upon the cylindrical projection and close the hatchway, a frame having a stop plate spaced above the hatch opening for limiting the outward movement of the hatch by engagement therewith, a guide bearing within the hatch opening, a second guide bearing at the stop plate, a rod secured to the hatch and extending vertically outward through the guide bearing in the stop plate and inwardly through the guide bearing in the hatchway, said hatchway being arranged to form an annular groove containing a sealing material and said hatch having a rib arranged to extend into said groove.
11. The combination with a closed tank having a hatchway, and a movable hatch for closing the hatchway, of means for guiding the hatch in a straight line motion, and
- stop means disposed above said hatch and adapted to be engaged thereby when it is forcibly raised for positively limiting the upward movement thereof.
12. The combination with a closed tank having a hatchway, and a movable hatch for closing the hatchway, having a substantially horizontal plane upper surface throughout a substantial portion of its area, of means for guiding the hatch in a vertical motion, and rigid stop means disposed above said hatch and having a substantially horizontal lower surface adapted to be engaged by the substantially horizontal upper surface of said hatch when it is forcibly raised for positively limiting its upward movement.
13. The combination with a closed tank, a cylindrical projection extending vertically upward therefrom forming a hatchway, and means associated with the upper periphery of said cylindrical projection for forming an annular groove, containing a sealing material, of a movable hatch adapted to rest upon the upper periphery of said cylindrical projection and having a downwardly extending flange entering into the sealing material in said annular groove to form an effective seal, and also having a downwardly extending peripheral flange disposed beyond the outer wall of said annular groove to prevent the entrance of water therein, means for guiding the vertical movement of said movable hatch, and rigid stop means disposed above said hatch and adapted to be engaged thereby for positively limiting the upward movement thereof.
14. The combination with a closed tank having a hatchway, a hatch adapted to close the hatchway, a rod attached to the hatch, a guide bearing for the rod to allow the hatch to open and close, and a single means for supporting said guide bearing and for limiting the outward movement of the hatch.

In witness whereof, I have hereunto set my hand and seal this 27th day of January, 1920.

BURTON E. HULL.
